UNITED STATES PATENT OFFICE.

ALICE COATES, OF HAMILTON, NEW ZEALAND.

HAT-PIN GUARD.

1,103,899.

Specification of Letters Patent. Patented July 14, 1914.

Application filed January 6, 1914. Serial No. 810,593.

To all whom it may concern:

Be it known that I, ALICE COATES, a citizen of the Dominion of New Zealand, and residing at Hamilton, in the Provincial District of Auckland, in the Dominion of New Zealand, have invented certain new and useful Improvements in Hat-Pin Guards, of which the following is a specification.

This invention relates to devices employed for covering the points of hat pins when in use, and thereby preventing damage which might occur with an unprotected point.

The invention consists of a wire made to fit upon a hat, either by following the contour around the inside or outside of the crown of the hat, or by fitting across the inside of the crown. The ends of the wire are provided with or formed into loops which extend along opposing sides of the hat.

The loop upon the left side of the hat is provided with a shield made of sheet metal or other material which will resist penetration by a hat pin. The shield is attached to its loop by arms, and in the space between the loop end and the shield a thickness of cork is provided wherein the points of the pins may be inserted without detriment to their sharpness. When used upon the outside of a hat, the shield is made ornamental or is covered by the trimming of the hat.

The invention as applied to the outside of a hat is illustrated in the accompanying drawing.

Figure 1, is a cross section of a hat with the guard fixed upon the outside thereof. Fig. 2, is a sectional plan on line A—A, Fig. 1, and, Fig. 3, is a perspective view of the guard.

Referring to the drawing, the wire, 1, is bent into a substantially semi-circular shape to fit around the crown of the hat 2, and is provided at its ends with loops 3 and 4, which extend along opposing sides of the hat. The central part of the wire thereby forms a connection for said loops. The loop, 3, is provided with a shield, 5, attached to

the loop by arms, 6. The shield corresponds in size to the size of its loop, so that a pin passed through the loop will be arrested by the shield. In the space between the shield and the loop a layer of cork, 7, is provided.

The guard is attached to the hat by stitching or other suitable means, and after the hat has been placed upon the wearer's hair, the hat pins, 8, are pushed through the loop, 4, and through the wearer's hair and the loop, 3, until they are stopped by the shield, 5. The cork, 7, is pierced by the pins, 8, which are held thereby without damage to their points.

What I do claim and desire to secure by Letters Patent of the United States is:

1. A guard of the kind described comprising a wire bent into loops at its ends so that the central part of said wire forms a connection for said loops, one of said loops being adapted to lie against one side of the crown of the hat and the other against the opposing side, a shield corresponding in size to one of the loops, arms connecting said shield to said loop, and a layer of cork inserted between said shield and the adjacent loop.

2. A guard of the kind described comprising a wire bent into substantially semi-circular shape so as to fit around the crown of the hat, an elongated loop formed at one end of said wire so as to lie against one side of the crown of the hat, an elongated loop formed at the other end of said wire so as to lie against the opposing side of the crown of the hat, a shield corresponding in size to one of the loops, arms connecting said shield to said loop, and a layer of cork inserted between said shield and the adjacent loop.

In testimony whereof I have signed my name to this specification in the presence of two witnesses.

ALICE COATES.
